No. 835,592.

PATENTED NOV. 13, 1906.

I. C. BANDMAN.
STATION INDICATOR.

APPLICATION FILED AUG. 30, 1905.

UNITED STATES PATENT OFFICE.

ISIDORE C. BANDMAN, OF NEW YORK, N. Y.

STATION-INDICATOR.

No. 335,592.

Specification of Letters Patent.

Patented Nov. 13, 1906.

Application filed August 30, 1905. Serial No. 276,470.

To all whom it may concern:

Be it known that I, ISIDORE C. BANDMAN, a citizen of the United States, and a resident of the city of New York, borough of Manhattan, in the county and State of New York, have invented a new and Improved Station-Indicator, of which the following is a full, clear, and exact description.

My invention relates to a device adapted to be used for many purposes, but particularly applicable for announcing stations on railways and the like. While capable of use on all kinds of railways, street-cars, and the like, it is especially designed for that character of trains in which the gates or doors cannot be opened except when the train stops at a station—as, for example, the ordinary elevated and subway trains.

Among the objects of the invention are the provision of means whereby when the gate or door is opened or closed a movement is given to certain parts of the device so as to change the sign displayed, also to provide for announcing the stations in regular order, either forward or backward, according to the direction of motion of the train, and the provision of very simple means for shifting the operating mechanism in such a way as to change the direction of motion of the sheet bearing the names of the stations.

Further objects of the invention will appear below.

Reference is to be had to the accompanying drawings, forming a part of this specification, in which similar characters of reference indicate corresponding parts in all the figures.

Figure 1 is a perspective view of a portion of a car, showing outside connecting devices for the indicator. Fig. 2 is a front view of an indicator, partly broken away, to show interior construction. Fig. 3 is a rear view, also partly broken away and in section and showing interior construction. Fig. 4 is a sectional view on line 4-4 of Fig. 3, and Fig. 5 is an end view of a support for carrying the station-indicating sheet.

Elevated and subway trains are usually provided with gates which are not intended to be opened except when the train is at a station. Therefore the opening or closing of the gate is an indication of the passage through a station, and the number of stations passed will be shown by the number of times the gate has been opened and closed.

In the drawings I have indicated a gate

10, which is provided with a link 11, a slide 12, and an operating-lever 13 of the ordinary construction. Connected with the slide 12 is a flexible member 14, which is properly guided to a position near the top of the car, where it is connected with a lever 15. This lever is oscillatably mounted upon a shaft 16 and carries a pair of pawls 17, which are forced by springs 17a into engagement with ratchet-wheels 18 and 19 near opposite ends of the shaft 16. These ratchet-wheels are placed with their teeth facing in opposite directions, so that as the lever is oscillated about the shaft it will draw one of the pawls 17 over one of the ratchet-wheels without operating it, but will engage the other pawl with the teeth of the other wheel so as to turn the second ratchet-wheel with the lever in one direction.

Connected with the ratchet-wheels are cones 20 and 21. These cones are adapted to engage a clutch member 22, and, in fact, they form companion members for said clutch member. This clutch member is rigidly connected with a gear 25, which in turn is connected with a pinion 24 on a shaft 23. This shaft carries a support 26, which I have shown as being square in cross-section and extending across the indicator. This support is provided with means for engaging and winding up a sheet 27, carrying the names of the stations. This means in the present instance is shown in the form of a series of pins 28 for engaging perforations 29 in the edge of the sheet. This sheet is designed to be wound up upon a drum 30, mounted on a shaft 31 and provided with a spring 32 for normally keeping the sheet wound upon the drum when not operated upon by the mechanism described above.

I have shown a groove 33 connected with each of the ratchet-wheels 18 and 19, and in these grooves are adapted to engage a pair of fingers 34, mounted upon a sliding bar 35, having a handle 36 on the outside of the indicator. I have shown the indicator as being mounted in a casing 37, through a slot 38 of which the lever 15 projects. This casing is also provided with an opening 39 opposite the support 26, through which the sheet 27 can be observed by the passengers.

The operation of the device is as follows: When the lever 13 is operated to open the gate, the flexible member 14 is pulled by the slide 12, which depresses the lever 15. This operation of the lever about the shaft 16 re-

sults in turning one of the ratchet-wheels with it, but leaves the other in stationary position. When the gate is again closed, the lever is brought to its original position by 5 means of a spring 40, and this operates the ratchet-wheels in the opposite manner, leaving the one which it moved before in a stationary position and moving the other in the reverse direction. The handle 36 being either 10 pulled out or pushed in, one of the cones 20 or 21 will engage with the clutch member 22 and the other will be free from it. Consequently the operation of the lever through a complete oscillation will operate through one of the 15 cones to the clutch member 22 and rotate the wheel 25 in either direction, according to the position of the sliding rod 35. This operation of the wheel 25 is timed to rotate the support 26 through a sufficient part of a revolution to 20 display a different name behind the opening 39. In the present instance it would rotate it through an arc of ninety degrees. It will be seen from this description that every time 25 a train passes the station the name of that station is removed from the observation of the passengers and that of the next station is displayed, all the operations being performed automatically and requiring no attention on the part of the brakeman or conductor.

30 Having thus described my invention, I claim as new and desire to secure by Letters Patent—

1. A station-indicator, comprising a movable support, a shaft connected with the support, a pair of ratchet-wheels, a lever, pawls 35 on the lever, said pawls being adapted to rotate the ratchet-wheels in opposite direc-

tions, and a clutch for connecting one ratchet-wheel with the shaft and disconnecting the other therefrom.

2. A station-indicator, comprising a rotatable support, a wheel for rotating the support, a shaft on which said wheel is mounted, a lever oscillatably mounted on the shaft, a pair of ratchet-wheels on the shaft facing in opposite directions, a pair of pawls on the lever for engaging said ratchet wheels, and means for throwing one of said ratchet-wheels into operative connection with respect to the first-named wheel and simultaneously throwing the other ratchet-wheel out of engagement with the first-named wheel, said means comprising a reciprocable bar.

3. A station-indicator comprising a rotatable support, a wheel for rotating the support, a shaft on which said wheel is mounted, a lever connected with the shaft, a pair of wheels located on the shaft on opposite sides of the first wheel, means connected with the lever for engaging the pair of wheels, means connected with each of said pair of wheels for rotating the shaft in one direction, and means for throwing one of the pair of wheels into operative connection with respect to the first-named wheel and simultaneously throwing the other of said pair of wheels out of engagement therewith.

In testimony whereof I have signed my name to this specification in the presence of two subscribing witnesses.

ISIDORE C. BANDMAN.
